UNITED STATES PATENT OFFICE.

JOHN P. WARD, OF CLEVELAND, AND ROBERT E. HYDE, OF CLEVELAND HEIGHTS,
OHIO, ASSIGNEES OF ONE-THIRD TO HARRY J. GREEN, OF CLEVELAND, OHIO.

CAR-DOOR LOCK.

Application filed April 4, 1927. Serial No. 180,657.

Our invention pertains to a lock that is especially adapted for use in connection with the doors of freight cars, and its primary purpose is to provide a device of this character that acts automatically to lock the door when the latter is moved to closed position and which is adapted to be released by power means whose actuating medium is conveniently accessible only to authorized persons.

A further object is to provide a lock for freight car doors that is very compact and that is designed to be so mounted in adjacent parts of the door and door frame as not to offer obstructions on which objects may catch when passed through the door opening.

Other objects are to provide a lock of the aforesaid character that is very strong and durable and is practically immune from disorder; that is simple and relatively inexpensive, and is adapted to be operated from a point remote from the location of the lock; that incorporates electrical means for actuating the locking head and which involves separable connections of such a nature as will avoid arcing within the car structure and thus eliminate the danger of fire from such cause; that includes, also, pressure fluid means for actuating the locking head, the presence of which does not interfere in any way with the operation of the electrical means (it being understood, however, that, so far as certain phases of the invention are concerned, either or both of these actuating means, or in some cases a substitute therefor, may be employed); and, further, to provide a lock of the aforesaid class that allows for a certain amount of sagging or excessive movement of the door with respect to the car body, such abnormal conditions being not unusual in rolling stock of the kind under consideration.

The foregoing objects, with other and more limited ones hereinafter appearing, are attained in the embodiments of our invention illustrated in the accompanying drawings wherein Fig. 1 is a vertical sectional view of parts of the car door and body in the vicinity of the lock, the section being taken substantially on the line 1—1 of Fig. 2; Fig. 2 is a horizontal section on the correspondingly numbered line of Fig. 1; Fig. 3 is an enlarged sectional detail on the lines 3—3 of Figs. 1 and 2; Fig. 4 is a view similar to Fig. 1 of a modification of the invention; and Fig. 5 is a

section on the line 5—5 of Fig. 4, the latter view being on a somewhat enlarged scale.

In the drawings, the car door is designated 1 and, in accordance with common practice, its edge is bound by a metal angle 2. The door is slidably mounted upon the side of the car body and, when in closed position, the angle 2 reposes within a Z-bar 3 which is secured by bolts 4 to the door post 5. The siding 6 and the lining 7 of the car body are fastened to the post, the latter being rabbeted for the reception of the ends of said siding and lining. The post 5 is mortised along its outer side adjacent the door opening for the accommodation of the lock that is designated generally by the reference numeral 10, and the door 1 is shown as having a depression on its inner side for the accommodation of a base or plate 11 from which a latch member 12 projects inwardly. The plate or base 11 is secured to the door by bolts 13 which have nuts 14 applied to their inner ends, and the plate is preferably recessed for the accommodation of said nuts. While we do not regard it so essential that the base or plate 11 be set within the door, we do prefer to counterbore the holes that accommodate the bolts 13 and extend into said counterbores depressed portions 15 of the plate so as to prevent any shearing strains being imposed on the bolts which might be the case if the plate 11 were engaged against the inner surface of the door.

The lock 10 is comprised of a casing that is made up of inner and outer members 18 and 19, respectively, that are angular in cross section, as best shown in Fig. 2, and said members have registering apertured ears 18^a and 19^a through which bolts are extended for holding the members together and for securing the lock within the mortise of the post. Certain of the bolts 4 that hold the Z-bar 3 in position are utilized for holding the casing members together on one side, the bolts which cooperate with the inner lugs of the casing being designated 20 and extending at right angles to the former bolts 4. Mounted within the casing at about the longitudinal center is a housing consisting of an angular wall 21 and end walls 22 and 23. A C-shaped locking head 25 is reciprocable within said housing and the same involves a nose 26 whose outer surface is inclined downwardly and inwardly for cooperation with the advancing inclined surface of the latch member 12. The

locking head is freely reciprocable within the housing and drops by gravity to locking position, in which position it is illustrated in the drawings. A cylindrical stem 28 rises from the locking head 25 through an aperture in the end wall 22 and constitutes the movable core of a solenoid 29. When this solenoid is energized the stem 28 is attracted upwardly so as to elevate the locking head and retract its nose 26 above the upper edge of the latch member 12 thereby to release the door.

This same result may be accomplished by pneumatic means which we shall now describe. Occupying the casing 10 below the wall 23 is a cylinder 30 within which a piston 31 reciprocates, and a rod 32 that is carried by the piston is projected through an opening in the wall 23 in a position to strike the base of the locking head 25. Accordingly, when compressed air or other pressure fluid is introduced into the lower end of the cylinder 30, it will lift the piston and, through the intervention of the rod 32, elevate the locking head so as to release the latch member 12 in the same manner as above described. A spring 33 is interposed between the piston 31 and the wall 23 and is of sufficient power to overcome the friction of the piston with the cylinder wall and depress the former when the pressure fluid is released from the cylinder.

Current is supplied to the solenoid 29 through a cable 35, and pressure fluid is conveyed to the cylinder 30 through a pipe 36. Mounted upon the car body in any convenient location is a terminal plate 38. The pipe 36 and the conductor 35 are led to the terminal plate 38 and the former is connected to it in any suitable manner so that a hose coupling may be applied to the end of the pipe. Such a connection is a common mechanical expedient and therefore specific illustration is deemed unnecessary. Set within a boss of the plate 38 is a terminal block 40 of insulating material enclosing split sleeves 41 of usual form which have binding posts at their inner ends to which the wires of the cable 35 are secured. The sleeves 41 receive pins 42 which are carried by a head 45 on the end of a cable 46 that may lead from a portable battery or any other suitable source of current. The head 45 incorporates a standard push button switch, the button of which is designated 47. By this means the connections are made between the head and the terminal block 40 while the current is cut off from the pins 42 and after the connection is made the push button 47 may be depressed to close the switch and introduce current through the connections to the winding of the solenoid 29. This arrangement avoids any possibility of an arc occurring within the installation in the car body which might result in a fire or explosion if inflammable material or explosives were in the car. Ordinarily the air and

electric terminals that are carried by the plate 38 are shielded by a cover 48 that is pivoted at 49 to the plate, and adjacent its free edge the cover has an opening 50 through which a plug 51 projects when the plate is in closed position, said lug having a perforation for the application of the wire of a freight car seal.

As above explained, when the door 1 is slid to closed position the latch member 12 engages the nose 26 of the locking head 25 and lifts said head until the latch member passes the vertical plane of the nose when the head drops with its nose to the rear of the latch member and secures the door to closed position. When it is desired to open the car, the cover 48 is raised and, if the operator uses electricity for operating the lock, he plugs the pins 42 of the head 45 into the sockets of the terminal block 40 and presses the button 47 thereby to transmit current to the winding of the solenoid 29 through the cable 35. Upon being thus energized, the solenoid attracts upwardly the stem 28 and elevates the locking head to release the latch member 12 when the door may be slid to open position. The side of the door frame opposite the one containing the lock 10 is preferably recessed for the accommodation of the latch member 12 when the door is fully open so that the door may be moved entirely out of register with the door opening and thus render the entire area of the door opening available for loading and unloading purposes. This is such an obvious feature that specific illustration is thought to be unnecessary. In this connection, attention is called to the fact that the lock involves no protruding parts on which objects might accidentally catch.

The electric current for operating the lock may be obtained from any suitable source, it being our intention that the operators authorized to open the cars be supplied with portable batteries each of which is equipped with a cable 46.

When pressure fluid is used to operate the lock, it may be obtained from the usual compressed air supplies found at railroad terminals, or from the train line. While we have shown the terminal plate 39 as located adjacent the lock, this may of course be located anywhere on the car body, on the roof, beneath the edge of the car, or where it would be least likely to be tampered with unnoticed by the train crew.

The modification illustrated in Figs. 4 and 5 differs from that above described principally in the location of the pressure fluid cylinder. Here the cylinder, designated 55, is located above the solenoid and the same is provided with a central tube 56 through which a pin 57 of brass or other non-magnetic material extends, the lower end of the pin being screwed into the stem which constitutes the core of the solenoid. The pin has a head

58 that is adapted to be engaged by the upper end of a sleeve 59 that terminates at its lower end in an annular piston 60 that operates within the cylinder. A head 61 is screwed or otherwise secured to the upper end of the cylinder, and a spring 62 is compressed between said head and the piston. The remaining parts of the structure are designated by the same reference characters as are applied to 10 the corresponding elements of the previously described embodiment. When the solenoid 29 of the present form of the invention is energized it attracts the stem 28 upwardly thereby to lift the locking head 25, and during 15 this operation the pin 57 rises through the upper end of the sleeve 59. On the other hand, when pressure fluid is admitted to the cylinder 55 it lifts the piston 60 with its sleeve 59 and the latter, engaging the head 58, lifts the 20 pin 57, the stem 28 and the locking head 25.

Having thus described our invention, what we claim is:—

1. A lock of the class set forth comprising a casing having an opening in its side, a locking head of material length having a sliding fit within the casing and restricted thereby to a vertical movement, a latch member adapted to be projected through said opening into the casing for interlocking engagement with the locking head, a stem on said locking head, and a solenoid whose core is constituted of said stem mounted within the casing.

2. A lock of the class set forth comprising a casing having an opening in its side, a C-shaped locking head having a sliding fit within the casing and having a depending nose on the side corresponding to the open side of the C, a latch member adapted to be projected through the opening in the casing and engage 40 the nose of the locking head, the latch member co-acting with the nose in the nature of a cam to lift the locking head as the member enters the casing, the head dropping by gravity to dispose the nose on the rear side of the 45 latch member, and means for elevating the locking head.

3. A lock of the class set forth comprising a casing having walls that are disposed at substantially right angles to each other and 50 provided with an opening which occupies parts of both walls, a plate having a laterally extending latch member that is adapted to be projected through said opening by movement of the plate in a plane substantially parallel with one of said walls, a substantially C-shaped locking head reciprocable within the casing in the region of said opening and having a depending nose on the side corresponding to the open side of the C, the latch member being designed to cooperate with said nose 55 in the nature of a cam to elevate the locking head as said member enters the casing, the head dropping by gravity to project said

nose to the rear of the latch member, and means for elevating the locking head. 65

4. A lock of the class set forth comprising a casing having an opening in its side, a locking head reciprocable within the casing, a latch member adapted to be projected through the opening in the casing for interlocking engagement with the locking head, and two power units that are adapted to act independently of each other for lifting the locking head thereby to release the latch member. 70

5. In a lock of the class set forth, the combination of a casing comprising opposed members, each member being angular in cross section and fitting together in opposed relation so as to effect a rectangular cross section for the casing, the opposed casing members having registering parts through which the members are adapted to be secured together, the casing having an opening in its side, a locking head reciprocable within the casing in the region of said opening, a latch member adapted to be projected through said opening for interlocking engagement with the locking head, and means for reciprocating the locking head. 75

6. A lock of the class set forth comprising a two part longitudinally divided casing having an opening in its side, means for securing the two parts of the casing together, a housing disposed within the casing in the region of said opening, the top 80 wall of the housing having an aperture, a locking head having a sliding fit within the housing, a latch member adapted to be projected through the opening in the casing for interlocking engagement with the locking head, a stem rising from the locking head and extending through the aperture in the top wall of the housing, and a solenoid surmounting said top wall and whose core is constituted of said stem. 85

7. A lock of the class set forth comprising a two part longitudinally divided casing having an opening in its side, means for securing the parts of the casing together, a housing disposed within the casing in the region of said opening, the bottom wall of the housing having an aperture, a locking head having a sliding fit within said housing, a latch member adapted to be projected through the opening in the casing for interlocking engagement with the locking head, a pressure fluid cylinder occupying the lower portion of the casing, a piston within said cylinder, and a rod rising from said piston and arranged to be projected through the aperture in the bottom wall of the housing for lifting the locking head. 90

In testimony whereof, we hereunto affix our signatures.

JOHN P. WARD.
